APPARATUS FOR THE PRODUCTION OF HIGH TENACITY VISCOSE RAYON YARN

Bob De Gee, Arnhem, Netherlands, assignor to American Enka Corporation, Enka, N.C., a corporation of Delaware

Application March 21, 1957, Serial No. 647,560

Claims priority, application Netherlands April 11, 1956

6 Claims. (Cl. 18—8)

The present invention relates in general to the manufacture of rayon and more particularly to an apparatus that can be used efficiently for manufacturing high strength viscose rayon yarn at high spinning speeds.

Extensive research is continually conducted by viscose rayon manufacturers to find methods of improving the physical properties of yarn. When rayon cord is used in tires and other rubber products, the strength and resistance to flex fatigue is most important. To meet this problem, the rayon industry has been able in recent years to supply its customers with yarns of greatly enhanced properties.

In the ordinary production of high tenacity yarn, viscose is extruded into a bath containing sulfuric acid, sodium sulfate and zinc sulfate. The freshly coagulated yarn, before it becomes completely regenerated, is stretched between two godets rotating at different speeds while passing through a hot weakly acidic bath.

Recently, it has been discovered in the rayon industry that certain chemicals, referred to generally in the art as viscose modifiers, alter and retard the coagulation-regeneration process of viscose in a very favorable manner. The modifiers not only cause a pronounced change in the molecular structure of the regenerated cellulose but also retard the regeneration process.

With the regeneration being retarded, the yarns remain in a plastic state longer which enables the yarn to be subsequently treated in a variety of ways heretofore not possible, such as imparting an even greater stretch to the yarn. By the use of modifiers, rayon yarn of the extra high tenacity type may be produced.

Many viscose modifiers are known in the art today and include polyalkoxy glycols or their reaction products with certain amines, alcohols, fatty acids and aromatic acids, certain aliphatic or aromatic monoamines, diamines and polyamines, certain quaternary ammonium compounds or heterocyclic bases, certain monocarbamates or dithiocarbamates, and others.

Also, recent experiments indicate that viscose yarn of even higher tenacity and higher fatigue resistance may be obtained by spinning viscose into a spinbath of relatively low sulfuric acid content of about 4.0—7.0%.

However, by employing either the low acid, modifier, or the combination of the two, the yarn may remain in a tender stage for a longer period of time than in ordinary viscose spinning. And, accordingly the need of protecting the tender yarn for a longer period arises.

With the regeneration process being retarded, the yarn is very sensitive to break and rupture. Also, the spinning speed of the yarn must be greatly reduced if the ordinary viscose spinning apparatus is used. In many instances, the reduction of speed is so great that the cost of production increases to such an extent that the cost of high tenacity viscose yarn may be no longer competitive.

Furthermore, the viscose rayon spinning apparatus represents a tremendous financial investment and may not be conveniently altered without incurring a great expense.

2

Hence, a need exists for spinning viscose yarn at an economical speed while using the known spinning techniques of low acid spinning and chemical modification without altering the ordinary spinning apparatus to a large extent.

In copending application, Serial No. 556,256, assigned to the present assignee, there is disclosed a method and apparatus by which viscose spinning speeds may be substantially increased by means of a two-diameter tube in the spinbath. By this arrangement the yarn is spun in the smaller tube portion and thereafter drawn through a second larger portion of the tube. The moving yarn causes the liquid in the spinbath to flow in the same direction as the yarn travel. The liquid flowing into the larger tube portion creates a pumping action on the liquid in the smaller tube portion. In this way the yarn may be initially subjected to the treating liquid in the spinbath under a minimal tension without adverse liquid turbulence while the yarn in the tube is in a tender stage.

Another apparatus for regenerating freshly spun yarn while traveling through a confined liquid treating tube is disclosed in U.S. Patent No. 2,440,057. In this patent the liquid is abruptly separated from the yarn. This abrupt separation subjects the yarn to considerable transverse force which is highly undesirable when the yarn is in a tender stage.

An object of the present invention is to provide a new and improved tube spinning assembly for the spinning of viscose rayon yarn of enhanced physical properties at a relatively high spinning speed.

Another object of the present invention is to provide a new and improved tube spinning assembly for removing from the spinbath viscose rayon yarn which has not been completely regenerated and which is still sensitive to transverse forces.

Still another object is to accomplish the above objects without greatly modifying the ordinary spinning machine employed by the viscose rayon industry.

These and other objects will become apparent from the following more complete description of the instant invention.

In accordance with the present invention the objects are accomplished by extruding viscose through a spinneret into a conventional spinning trough containing a coagulation-regeneration liquid, directing the yarn and spinbath liquid through a spinning tube mounted adjacent to and concentric with the spinneret, discharging the spinbath liquid and yarn into an inner container of spinbath liquid and thereafter separating the liquid and yarn. The velocity of the liquid moving co-currently with the threads is diminished practically to a standstill at which point the yarn and liquid are separated. The direction of yarn travel from the spinneret to the point of separation from spinbath is preferably inclined upwardly and generally in a straight line. The process may be carried out while using a chemical modifier and spinning conditions which retard the regeneration of the viscose.

Figure 1 is a diagrammatic view of a section taken along the line 1—1 in Figure 2.

Figure 2 is a plan view of one spinning point, showing a preferred embodiment of the invention with the tube spinning assembly being angularly positioned in a spinning trough.

The drawings are given to facilitate a complete understanding of the invention. For this reason the precise structural details of the apparatus are omitted, as forming no part of the present invention. Although a most important advantage of the present invention lies in the fact that a plurality of spinning assemblies may be used in one elongated conventional spinning trough, for convenience the present invention will be discussed and illustrated while making reference to only one spinning point.

Referring now to the drawing and more particularly to Figure 1, reference numeral 1 represents an elongated spinning trough which contains coagulating-regenerating liquid referred to herein as spinbath and designated generally by number 2. Within the trough there is positioned a spinning assembly comprising an upwardly inclined two-diameter spinning tube 3, adjacent to and concentric with a spinneret 4, said tube 3 extending into an inner spinning tray, designated generally with reference number 5. For the purpose of easily controlling the flowing stream of spinbath in the spinning tube, the spinning assembly should be arranged so that the spinning tube is upwardly inclined. Also, in this manner the present invention may be conveniently adapted for use in conventional spinning machines.

A viscose solution is pumped to and through spinneret 4. The direction of the flow of viscose is shown by arrow 6. As the viscose is extruded through the spinneret 4, it coagulates and forms threads 7 which are directed into and through the spinning tube 3.

The spinning tube 3, preferably made from glass, consists of a narrow portion 8 and a wide portion 9 connected by a frusto-conical portion 10. Supporting bracket 11, attached to the bottom of the spinning trough 1, holds the tube 3 aligned with and in spaced relation with respect to the face of the spinneret 4. The tube 3 is snugly held by supporting bracket 11 but is conveniently removable therefrom. The free end of the wide tube portion 9 passes through an opening in the wall 12 of tray 5 in a liquid tight manner. Here, the sealing may be affected by means of a washer made from any flexible, resilient, acid resistant material arranged between the tube and the edge of the opening in the wall 12 in a known manner and therefore not further indicated in this description. However, an elastic connection between the tube and tray is preferred.

Immediately after the viscose is extruded into spinbath 2, the threads 7 are in an extremely tender stage and are moved with a minimum tension through the narrow tube portion 8 by the spinbath 2 flowing rapidly in a co-current direction with the yarn. Upon entering the wide tube portion 9, the threads are partially regenerated and are spread out in a manner which enables a more intimate contact of the individual threads with the now weaker spinbath liquid. In the wide portion of the tube the liquid moves at a slower velocity and more tension is required to pull the threads therethrough. However, in this stage the yarn may be subjected to a greater longitudinal tensioning inasmuch as the threads have become regenerated to a greater degree.

The inner spinning tray 5, supported within trough 1 in any known manner, is an open top container defined by walls 12, 13, 14 and 15, which extend above the level of the liquid in spinning trough 1. The walls may form an integral part of the trough or may be separate therefrom as shown in Figure 2.

The interior of tray 5 is divided into upper and lower compartments by a false bottom 16, which is perforated as at 17 and which is secured to the walls of the tray above the tray bottom 18. Discharge opening 19 is provided in tray bottom 18 for draining the lower compartment. The false bottom 16 is curved in an upward direction to form a wide overflow edge 20 which is parallel to and spaced from wall 13 but sealed to walls 12, 14 and 15 to provide a reservoir 21 for the liquid which has traveled from the spinning trough 1 through tube 3. The overflow edge 20 is in a plane below the top of wall 13.

Pipe 22 provides a confined passageway between opening 19 to its frusto-conical end 23 and fits with a correspondingly constructed outlet opening 24 located on the bottom of the spinning trough. In order to illustrate this, the tray 5 in Figure 1 is shown in a somewhat raised position. The excess spinbath liquid in reservoir 21 reaches the discharge pipe 22 by flowing over edge 75

20 and/or through the perforations 17. The liquid in discharge pipe 22 returns to a main spinbath supply point to be replenished with fresh spinbath which enters the spinning system through conduit 25. The bottom 18 together with pipe 22 and the walls 12, 13, 14 and 15 seals tray 5 from the spinning trough 1, except through the opening in wall 12 through which tube 3 extends.

On an adjustable support 26, affixed to a wall of tray 5, a pair of freely rotatable thread guiding rollers 27 and 28 is mounted nearer the overflow edge 20 with roller 27 contiguous to the top level of the spinbath in reservoir 21.

During the spinning operation the liquid level in the spinning trough 1 preferably may be maintained slightly higher than the liquid level in reservoir 21 as shown in Figure 1. This difference in levels assists the flow of the liquid through spinning tube 3.

The rayon threads 7 after leaving the tube 3 are directed through the liquid in reservoir 21. By proper location of thread rollers 27 and 28 and inclination of the tube 3, the threads 7 travel through the spinbath liquid entirely in a straight line. In other words, the individual threads never change their direction before they are withdrawn from the liquid at which point the stream of spinbath liquid has substantially come to a standstill. A most important feature of the present invention is the absence of turbulence of the spinbath liquid at the point where the threads are removed.

After wrapping several times around a conventional godet 29, the threads are delivered to points (not shown) for further aftertreatment in a known manner.

It has further been found that the current is most favorably minimized when the width of the tray is about 1.3 times the diameter of the discharge opening of the spinning tube.

A preferred embodiment of the present invention contemplates a plurality of perforations in the false bottom of the inner tray. In this way the excess liquid leaves the reservoir through a multitude of passageways which decreases the agitation of the liquid in the tray to a minimum. A more gradual and uniform carrying off of the spinbath liquid out of the tray is attained. In this manner the filaments are exposed to the smallest possible transverse forces inasmuch as the yarn is guided out of the liquid only after the flow of liquid has almost come to a standstill.

Figure 2 shows the spinning assembly disposed in a diagonal position in the spinbath trough. This positioning may be preferred in order to arrange the most assemblies in a trough of given dimensions. The simplicity of construction of the spinning tube with the tray connected thereto enables adapting the usual spinning machines to tube spinning without radical modifications since a plurality of tubes with a corresponding number of trays may be easily placed in the ordinary elongated spinning trough and removed therefrom.

If desired, a grate may be arranged above the overflow edge to prevent threads from going thereover when the threads are first spun-in.

Although the location of the guiding rollers is not of utmost importance, it may be preferred, as shown in Figure 1, to locate the guiding rollers 27 and 28 in a perpendicular position near the overflow edge 20 where there is the least noticeable flow of liquid. Furthermore, it may also be preferred to arrange the first thread guiding roller so that the periphery of the roller is contiguous to the liquid in order to give better protection to the tender thread.

The parts of the apparatus that come in contact with the spinbath are made of material that is chemically resistant to the spinbath, such as lead.

The above improvement has been described with terms that are to be construed in their descriptive sense and not as terms of limitation; and it is intended that

all equivalents thereof be included within the scope of the appended claims.

What is claimed is:

1. Apparatus for producing viscose rayon yarn comprising a spinning trough containing a spinbath, a spinneret mounted within said trough, a tray positioned within said trough, said tray having walls and a bottom separating the interior thereof from the spinbath in said trough, a curved false bottom mounted in said tray, said false bottom dividing the interior of said tray into upper and lower compartments and providing an overflow edge for draining said upper compartment into said lower compartment, and a treating tube having one end positioned adjacent to and in coaxial alignment with the face of said spinneret and having the opposite end extending into the upper compartment of said tray, said treating tube providing the sole communication for the flow of spinbath from said trough to said tray.

2. Apparatus for producing viscose rayon yarn comprising a spinning trough containing a spinbath, a spinneret mounted within said trough, a tray positioned within said trough, said tray having walls and a bottom separating the interior thereof from the spinbath in said trough, a curved false bottom mounted in said tray, said false bottom dividing the interior of said tray into upper and lower compartments and providing an overflow edge for draining said upper compartment into said lower compartment in order to maintain a level of spinbath in the interior of said tray slightly lower than the level of spinbath in said trough, a treating tube having one end positioned adjacent to and in coaxial alignment with the face of said spinneret and having the opposite end extending into the upper compartment of said tray, said treating tube providing the sole communication for the flow of spinbath from said trough to said tray, and means for discharging spinbath from the lower compartment of said tray to the outside of said trough.

3. Apparatus as set forth in claim 2 wherein said false bottom is provided with a plurality of perforations.

4. Apparatus as set forth in claim 2 wherein the width

5 of said overflow edge is about 1.3 times the diameter of said treating tube.

5. Apparatus as set forth in claim 2 and further comprising guide means positioned substantially at the level of spinbath in said upper compartment for separating thread and spinbath flowing into the upper compartment of said tray.

6. Apparatus for producing viscose rayon yarn comprising an elongated spinning trough containing a spinbath, a spinneret mounted within said trough, a tray positioned within said trough, said tray having walls and a bottom separating the interior thereof from the spinbath in said trough, a curved and perforated false bottom mounted within said tray, said false bottom dividing the interior of said tray into upper and lower compartments and providing an overflow edge for draining said upper compartment into said lower compartment in order to maintain a level of spinbath in the interior of said tray slightly lower than the level of spinbath in said trough, a two-diameter treating tube having narrow and wide portions joined by a frustoconical portion, the free end of said narrow portion being positioned adjacent to and in coaxial alignment with the face of said spinneret and the free end of the wide portion extending into said compartment, said treating tube providing the sole communication for the flow of spinbath from said trough to said tray, a discharge pipe for draining the lower compartment of said tray through the bottom of said trough, and a thread guide mounted substantially at the level of spinbath in said upper compartment, said spinneret, treating tube and thread guide being positioned one with respect to the other so that thread extruded through said spinneret will travel in a substantially straight line from the face of the spinneret through the middle of the treating tube to the thread guide.
